UNITED STATES PATENT OFFICE.

JAMES W. PEARCE, OF PHILADELPHIA, PENNSYLVANIA, ASSIGNOR OF ONE-HALF TO LESTER C. KEYSER, OF PHILADELPHIA, PENNSYLVANIA.

FEED-WATER PURIFIER.

SPECIFICATION forming part of Letters Patent No. 694,571, dated March 4, 1902.

Application filed April 25, 1901. Serial No. 57,384. (No model.)

To all whom it may concern:

Be it known that I, JAMES W. PEARCE, a citizen of the United States, residing at Philadelphia, in the county of Philadelphia and 5 State of Pennsylvania, have invented new and useful Improvements in Feed-Water Purifiers, of which the following is a specification.

In my invented purifier the water from the feed-pipe passes through a series of compartments which communicate with each other by valves in the partitions separating the compartments, those nearer the top allowing the water to pass through them from the feed-pipe to the boiler and those nearer the bottom 10 allowing passage in the opposite direction. This construction permits the impurities in the water to settle in the different compartments, the clearer water in the upper portion of the compartment passing into the next, 15 while the muddier and dirtier portions remain in the compartment comparatively undisturbed, and the dirt is allowed to quietly settle out.

Describing now the best construction of my 20 invention, Figure 1 is a longitudinal section through the boiler and purifier. Fig. 2 is a cross-section on line Z Z of Fig. 1, and Fig. 3 is a perspective of the purifier apart from the boiler.

The boiler A is shown as a return tubular boiler; but my invention is applicable to any boiler having a sufficient open space to receive the purifier-box. The purifier-box D is placed within the boiler and has connected with it 25 the feed-pipe C. This pipe is suitably connected in any usual or convenient manner. The box D is provided with partitions G G, dividing it into compartments. In the upper part of these partitions are the ports E E, 30 which are closed by the valves F F, that open only in the direction of the movement of the water through the box into the boiler. With the first of these compartments the feed-pipe C communicates. In the lower part of the 35 partitions G G are placed the ports J J, closed by the valves H H, that open in the opposite direction from the valves F F and allow passage in the opposite direction. From the last compartment of the box D the water flows 40 into the boiler, and for this purpose a depression, as d, is generally provided.

The purifier-box can be kept away from the bottom of the boiler A by hangers K K or otherwise suitably supported and can be of any convenient shape in cross-section; but 55 an elliptical shape has some advantages in enabling it to be more readily entered into the boiler by the manhole. It is preferably closed for a portion of its length at the top and is generally placed so that the top of the 60 box is a little higher than the water-level in the boiler.

Means are provided by which the feed-pipe C can be converted into a boiler-exhaust pipe. A very convenient form is that shown in Fig. 65 1, where the pipe C communicates with the pipe B, the portion L of which communicates with the source of feed-water and the portion M exhausts into the air or sewer, the valves X and Y determining which of the two the 70 pipe C shall form the continuation of. The water enters through pipe C one of the compartments. There it is comparatively undisturbed, and the mud settles down toward the bottom, the clearer water at the upper part 75 of the box passing through the port E to the next compartment. Here a further depositing out of the mud or sediment takes place, and again the clearer water flows out through port E into the next compartment. The wa- 80 ter after passing through the various compartments flows out from the box. It will be seen readily that it will be almost entirely cleared of mechanical and chemical impurities. The mud or sediment gathers at the 85 bottom of the various compartments. When the boiler is to be blown out, the valve X is closed and the valve Y is opened, and this pressure in the boiler drives the water forcibly out. The lower valves now open, and the mud, 90 sediment, and precipitate is driven through them out through the pipe C.

Having now described my invention, what I claim, and desire to secure by Letters Patent, is—

1. In a feed-water purifier, situated within the boiler, the combination of a series of compartments, water-passages at various heights connecting said compartments, a feed-water-inlet pipe opening into one of said compartments, an outlet for the feed-water into the boiler, and valves in said passages, the valve 95 100

in the upper passage opening in the direction of the flow of the water from the feed-pipe into the boiler, and the valve in the lower passage opening in the direction of the flow of the water from the boiler to the exhaust water pipe; substantially as described.

2. In a feed-water purifier the combination of a box, having a portion of the top thereof closed; partitions dividing the closed portions into compartments; a feed-pipe entering the closed end of the box; valves near the top of said partitions, opening in the direction of the flow of water from the feed-pipe; and valves near the bottom of said partitions, opening in the opposite direction to those in the upper part of the partitions; substantially as described.

3. In a feed-water purifier the combination of a box, partly inclosed at its top, but hav-

ing an open space lower and outlets therefrom into the boiler; supports for said box, maintaining it so that the said outlets are near the water-line of the boiler; partitions dividing the inclosed portion of the box into compartments; valves near the upper part of the partitions, opening toward the open end of the box; and valves in the lower portion of said partitions, opening toward the closed end of the box; a pipe leading into the lower part of the closed end of the box and means for converting this pipe into a boiler-exhaust pipe; substantially as described.

In testimony whereof I affix my signature in presence of two witnesses.

JAMES W. PEARCE.
